UNITED STATES PATENT OFFICE

WILLIAM M. SPRY, OF BEACHMONT, MASSACHUSETTS, ASSIGNOR TO THE PEERLESS MACHINERY COMPANY, OF BOSTON, MASSACHUSETTS, A CORPORATION OF MASSACHUSETTS

BUFFING MACHINE

Application filed April 18, 1927. Serial No. 184,764.

This invention relates to buffing machines and is herein shown as embodied in a machine for buffing soles, counters, box toes and similar leather parts used in the shoe manufacturing industry.

Heretofore, in machines of this class, it has been in a practical sense impossible to secure a perfectly smooth, finished surface without the expenditure of much time and effort. The sand or emery board used as a covering for the buffing roll generally contains hard particles which leave linear marks in the finished surface which are difficult to remove without subjecting the work to other operations, and increasing the cost thereof.

The principal object of my invention is the provision in a machine of the character described, of means for preventing any marks or grooves in the finished surface and for producing a surface which is perfectly smooth and unmarred.

To this end, my invention contemplates the provision in a buffing machine of means for guiding the work through the machine in a path oblique to the normal line of feed. When the work is thus guided, the presence of comparatively large and hard particles in the buffing surface does not produce any marring effect upon the surface and the work is finished smoothly in one passage through the machine.

Another object of the invention is the provision of guiding means adapted for preventing any buckling or twisting of the work as it is fed forward which may be due to the tendency of the rolls to carry the work forward in the normal line of feed.

I accomplish this object by providing guiding means so constructed that throughout its progress through the machine the work is in engagement with fixed abutting surfaces for opposing the thrust of the work due to the action of the rolls thereon whereby the work is supported and held in its oblique line of travel.

A further object of the invention is the provision of guiding means adjustable transversely of the machine and also to regulate the angle of obliquity of its path to suit various kinds of work and various conditions.

Other objects of the invention will be more specifically set forth and described hereinafter.

In the accompanying drawings, illustrating one form of my invention, Figure 1 is a plan view of the upper portion of a buffing machine of ordinary construction provided with means for guiding the work constructed in accordance with my invention; Fig. 2 is a front elevation of the same; Fig. 3 is a side elevation of the same; Fig. 4 is a vertical sectional view on line 4-4 in Fig. 1; Fig. 5 is a view partly in elevation and partly in section of one form of means for fastening the main guiding member in adjusted position; Fig. 6 is a plan view of a supplemental guiding member and means for securing it in adjusted position; Fig. 7 is a view in perspective of the buttressed end of one of the main guiding members; Fig. 8 is a plan view of one form of adjustable means for holding down the work preparatory to passing between the rolls and Fig. 9 is a side elevation of the same.

In the drawings illustrating my invention is shown one form thereof applied to a buffing machine of ordinary and well-known construction adapted for buffing soles, box-toes, and other shoe parts used in the shoe manufacturing industry. The upper part only of said machine is shown comprising the top plate 10 of a frame, a buffing roll 12, a co-operating feed roll 14 and a work support 16. The lower portion of the frame and the operating instrumentalities for rotating the feed and the buffing rolls are not shown since they are well-known in the art.

The top plate 10 is rectangular in form with a depending flange 18 and a transverse opening to permit the feed roll mounted above the top plate and the buffing roll mounted thereunder to engage and receive the work. The upper surface of the top plate 10 serves also to support the work and as a continuation of the work support 16 which is attached by screws 17 to brackets 19 fastened in turn to the flange 18 of the top plate by screws 21.

The buffing roll 12 is of ordinary construction having a covering 28 of abrasive material (Fig. 4) which is held in place by having its ends turned into a longitudinal slot 100

in the roll and held by a wedge strip 30, and is fixed upon a shaft 32 rotatably mounted in suitable bearings in the sides of the frame 10. The buffing roll engages the work through the transverse opening in the top-plate 10.

5 The feed roll 14 is provided with a comparatively thick resilient covering 34 of rubber or other similar material and is secured on a shaft 35 which is rotatably mounted in bearing blocks 36 carried by upright side plates 37. Each of the side plates has a bottom extension 38 (Figs. 1 and 3) connected to the top of the plate by a brace 39 to impart rigidity to the plate which may be fastened to the top-plate 10 by any suitable means as by screws 40 through the extension 38. The bearing blocks 36 slide vertically in recesses or runways formed in the side plates and are held therein by vertical strips 42 secured to the side plates by screws 43, the bearing blocks having grooves or channels formed in their two sides to receive the side plate and strip 42. The bearing blocks are thereby locked into the side plates but may be removed when necessary by unfastening the screws 43 and removing the strips 42. A tie bar 45 secured at each end to a bearing block by a screw 46 connects the two blocks so that the feed roll, bearing blocks and tie bar move 30 as a unit in the side plates.

For adjusting the feed roll vertically and for permitting it to yield slightly when necessary, the following means are provided. A top bar 48 may be secured by screw bolts 50 to the tops of the side plates 37 and midway the top bar is bored to receive loosely a screw 52, the lower portion of which is threaded into the tie bar 45 (Fig. 2). A laterally projecting shoulder 53, formed on the screw 52, engages the upper surface of the top bar 48 to prevent longitudinal movement of the screw in relation to the top bar and by means of a hand wheel 54, the screw 52 may be turned in one direction or the other to raise or to lower 45 the feed roll vertically and in relation to the buffing roll. A short lever 55 is threaded at one end on the screw 52 to serve as a convenient and rapid means for locking the screw 52 to the tie-bar 45 in adjusted position. Since the screw 52 is operated merely to raise and to lower the feed roll vertically and is loosely mounted in the top bar 48 there is nothing to prevent upward movement of the feed roll under the impetus of the work. To hold it in 50 a lowermost resilient position, a pair of springs 56 is interposed between the tie bar and the top bar, the tie bar being provided with round lugs 57 to receive the lower ends of the springs and to hold them against 55 lateral displacement. The top bar may be provided with circular upright bosses 60 bored and threaded to receive threaded nuts 62, the lower ends of which bear against the upper ends of the springs. In the head of 60 each nut are holes 64 to receive a pin where-

65 by the nuts may be turned downwardly or upwardly to increase or reduce the compression exerted by the spring upon the tie bar. The adjustment of the nuts 62 regulates the pressure exerted upon the tie-bar by the springs 56 and therefore the pressure exerted upon the work by the feed roll.

In the operation of the buffing machine just described, the buffing roll is rotated at a speed greater than the feed roll which tends to hold the work being buffed and to feed it at a slow speed while the abrasive surface on the rapidly turning buffing roll smooths the surface of the work presented thereto. The tendency of the work in going through the machine is normally to move along a straight path tangent to the lines of rotation of the rolls and it is practically impossible to feed by hand along a path oblique to the normal line of feed since the friction between the work and the buffing roll will, when the work is turned obliquely, throw it back to the normal line of feed. To feed the work obliquely, it is necessary that the work be fed in contact with guiding means which serves as a buttress, to prevent the work being twisted from the oblique path into the normal line of feed, such guiding means being arranged on the work support both in front and in rear of the rolls. Any suitable form of guiding 85 members which will hold the work along a line of movement oblique to the normal line of feed may be used and in the drawings I have shown one form of guiding means which is illustrative merely and to which I do not desire to be limited since such means may be constructed in various forms.

In the form shown, a guide strip 70 is fixed on the work-support 16 in front of the rolls at the desired angle of obliquity to the normal line of feed, the forward end of the strip being in close proximity to the point at which the rolls engage the work. The strip 70 is adjustably secured to a slide block 72 which is mounted in an elongated slot opening 73 (Figs. 1 and 5) in the work-support which opening extends transversely the work-support and is parallel to the rolls. The slot opening is formed with longitudinal shoulder portions 74 which support the slide-block 72 in any adjusted position, the upper face of the block being flush with the upper face of the work-support. Any suitable means may be employed for securing the strip and slide-block in position and one such is shown comprising a screw 75 and a butterfly nut 76 threaded thereon (Fig. 5). These members are so formed and arranged that the head of the screw overlaps the top surface of the guide strip 70 and the nut 76 engages the bottom surface of the work-support, and when the nut is tightened the guide strip, block, and work-support are all drawn into tight engagement preventing any relative movement of said members. The loosening 120

of the nut permits the slide block and guide strip to be moved as a unit transversely to the work-support along the slot opening and also permits the guide strip to be angularly adjusted in relation to the normal line of feed.

One advantage of this construction is that the work may be directed to any portion of the buffing roll desired and when one portion of the buffing surface of the roll is worn down the guide strip may be moved laterally to utilize another portion of the buffing surface. This is of importance when the work is narrow in width compared with the width of the buffing roll because it enables the entire buffing surface to be utilized to the fullest extent before being renewed.

To prevent the work being drawn over the forward end of the guide strip 70 by the action of the rolls, an upright abutment 78 may be formed thereon (Figs. 4 and 7) with its forward edge curved in parallelism with the surface of the feed roll. Any suitable device or means for preventing any upward curling of the work and for holding it down upon the work-support as it is fed into the rolls may be employed and one such is shown comprising a plate 80 (Figs. 8 and 9) loosely and pivotally mounted on a pin 81 held by a screw 82 in a bracket 83 secured by a screw 84 and a pin 85 to the guide strip 70. The plate is held in a downwardly position by the free ends of a spring 86 fastened midway by a screw 87 to the pin 81. Normally, the plate holds the work down by a light pressure but it may be raised by the operator any time to release the work through the instrumentality of a finger piece 90 formed as an extension of the plate. The pressure exerted upon the work by the plate may be regulated by a screw 91 threaded through an extension 92 of the bracket 83 and adapted to engage the finger-piece 90.

In order to prevent the work pivoting on the forward end of the guide strip 70 after a portion of it has passed through the rolls and thereby returning to a path along the normal line of feed, a second guiding strip 95 is preferably mounted on the work support in front of the rolls and parallel to the strip 70 and is held in adjusted position on a slide block 96 by a screw 97 and butterfly nut 98 of a construction similar to those elements used for fastening the guide strip 70. The two guide strips 70 and 95 should be sufficiently close together to engage lightly the two side edges of the work as it is fed forward along the desired path and therefore any movement of the rear portion of the work due to a pivoting action on the forward end of the guide 70 is prevented by the strip 95.

An additional guide member may be located in the rear of the rolls in alignment with the guide 70 when desired for certain types of work and one form is shown comprising a

short guide strip 100 (Fig. 6) secured by a screw 101 to a slide block 102 which is slidably mounted in a channel or groove 103 formed in the top surface of the top plate 10. The slide block 102 is provided with a longitudinal slot 104 and a binding screw 105 is located in said slot and threaded into the top-plate 10 for fastening the slide-block in adjusted position. The loosening of the screw 105 permits the slide-block 102 to be adjusted in a direction parallel to the rolls and transversely the machine.

The guide 100 may also be provided with an upright abutment 106, curved at one end to permit it to extend in between the rolls (Fig. 4); said abutment serving to engage the work after it emerges from the rolls and in case it curls upwardly.

Although I have shown, in the preferred form of my invention, three guiding members, the use of all three at any one time may not be necessary, especially when the work which is being buffed is stiff and unbending. In buffing thin and flexible work it will probably be found advantageous to use all three but in some cases it may not be absolutely necessary to do so.

In machines of this character it is generally customary to provide one or more brushing rolls for engaging the buffed surface of the work after it leaves the buffing roll to remove the dust and particles on the buffed surface and such a roll 110 is shown in Fig. 4, the shaft 112 of the roll being rotatably mounted in flanges 18 (Fig. 3) of the work-support. A weighted elongated plate 114 loosely mounted on two upright screws 115 serves to hold the work in engagement with the brushing roll 110 and a helical spring 116 is interposed on each screw 115 between its head and the plate to hold the latter to resist the upward thrust of the work when being cleaned.

For preventing injury to the hands of the operator when feeding the work, a guard rod or member 120 may be arranged in front of the rolls and at a height above the work support sufficient to permit freely the feeding of the work. The guard member may be mounted in any suitable manner but preferably is supported at each end by a segment bracket 121 pivotally mounted on a screw 122 set in the side flange 18 (Fig. 3), the upper corner of each bracket being in the form of a split collar bearing 123 to receive and hold one end of the guard member. A screw 124 is used to tighten the collar to hold the guard member securely in the bracket. The position of the guard in relation to the work-support and rolls is regulated by moving the brackets pivotally and to hold them in adjusted position, each bracket is provided with a segment slot 125 within which is mounted a screw 126 threaded into the depending flange 18. The head of the screw overlaps the sides of the slot and the loosening of the screw permits

the adjustment of the guard by the pivotal movement of the brackets.

In the operation of a buffing machine provided with guides made in accordance with my invention and with the buffing rolls properly adjusted to the work to be done, the guides are adjusted at the desired angle to the normal line of feed by manipulation of the butterfly nuts whereby they are fastened to the work-support. The work is then fed to the rolls by hand and between the guides and under the hold-down plate 80 provided one is used. In Fig. 1, I have shown work 130 in the form of a sole in position between the guides for entering between the rolls. As the work is fed forward, the friction between it and the rolls tends to turn the work from an angular path to the normal line of feed but the thrust of the work thus engendered is opposed by the guides and it is freed to proceed along the desired path. After the forward end of the work emerges from between the rolls, that end is supported by the guide in the rear of the rolls. In case the work is thin and flexible, the upright abutments 78 and 106 on the front and rear guides respectively prevent the work riding up over the guides adjacent the rolls.

By feeding the work through the machine at an angle, I avoid any cuts or lines in the finished buffed surface which otherwise might occur from solid particles on the surface of the buffing roll, and I have found that a perfectly smooth velvety surface is invariably secured.

It is to be understood that my invention is not to be limited to the specific form of construction herein shown and described as it may be embodied in various other forms all within the spirit thereof.

What I claim is:

1. In a machine of the class described, the combination with a work-support, a feed roll and a buffing roll of means for guiding and holding in flat condition thin flexible work fed obliquely through the machine comprising a guiding strip adjustably secured to said work-support obliquely to the normal line of feed and having its forward end provided with an upright side abutment to prevent the work riding up over the end of said guide, a second guiding strip behind said feed roll and said buffing roll and in alignment with said first guiding strip and a spring pressed plate of substantial width arranged in close proximity to said rolls and to the front end of said first mentioned guiding strip to hold that portion of the work about to be presented to the rolls in flat condition.

2. In a machine of the class described, the combination with a work-support, a feed roll and a buffing roll of means for guiding and holding in flat condition thin flexible work fed obliquely through the machine comprising an elongated guiding strip, said guiding

strip having its front end in close proximity to said feed roll and said buffing roll and having an upright side abutment thereon for preventing the work riding over said guiding strip, means for securing said guiding strip in adjusted oblique position on said work support, and a spring pressed plate of substantial width arranged in close proximity to said rolls and to the front end of said guide to hold that portion of the work about to be presented to the rolls in flat condition.

3. In a machine of the class described, the combination with a work support, a feed roll and a buffing roll of means for guiding and holding in flat condition thin flexible work fed obliquely through the machine comprising an elongated guiding strip adjustably secured to said work support oblique to the normal line of feed and having its forward end provided with an upright side abutment, the front edge of which follows the configuration of the feeding roll for preventing the work turning upwardly and over said guiding strip during its progress between said rolls, a second guiding strip behind said rolls and in alignment with said first guiding strip also provided with an abutment having one edge following the configuration of said feed roll and a spring pressed plate arranged in close proximity to said front guide adjacent said abutment thereon and projecting forwardly in between said feed roll and said buffing roll, in order to hold the work in flat condition and prevent turning the edge thereof when presented to the machine and during its progress therethrough.

4. In a machine of the class described, the combination with a work-support, a feed roll and a buffing roll of means for guiding and holding in flat condition thin flexible work fed obliquely through the machine comprising a pair of elongated guiding strips between which the work is fed, said strips being adjustably secured to said work support obliquely to the normal line of feed and one of said strips being provided on its forward end with an upright side abutment for preventing the work from turning upwardly and riding over said guiding strip during its feeding movement and a spring pressed plate of substantial width arranged in close proximity to the forward end of the guiding strip and to said rolls to hold that portion of the work about to be presented to the rolls in flat condition.

In witness whereof, I hereunto set my hand this fifteenth day of April, 1927.

WILLIAM M. SPRY.
